UNITED STATES PATENT OFFICE.

HENRY O. SCHMIDT, OF NEW YORK, N. Y.

DESIGN FOR A GRILLE.

No. 40,039.

Specification for Design.

Patented June 8, 1909.

Application filed April 12, 1909. Serial No. 489,539. Term of patent 7 years.

To all whom it may concern:

Be it known that I, HENRY O. SCHMIDT, a citizen of the United States, residing at New York, in the county of New York and State of New York, have invented a new, original, and ornamental Design for Grilles, of which the following is a specification, reference being had to the accompanying drawing, forming part thereof.

The figure is a perspective view of a grille, showing my new design.

I claim:

The ornamental design for a grille, as shown.

HENRY O. SCHMIDT.
